UNITED STATES PATENT OFFICE.

WILLIAM JINKINGS, OF LONDON, ENGLAND.

OPTICAL TOY.

SPECIFICATION forming part of Letters Patent No. 694,967, dated March 11, 1902.

Application filed June 17, 1901. Serial No. 64,897. (No model.)

To all whom it may concern:

Be it known that I, WILLIAM JINKINGS, a subject of the King of Great Britain, residing at 49 Gladsmuir road, Highgate, London, England, have invented Improvements in Optical Toys, (for which I have applied for a patent in Great Britain, No. 21,577, bearing date November 29, 1900,) of which the following is a specification.

My invention consists of a toy tent, preferably of the pointed or conical shape, within which at one side of the opening is fitted a piece of silvered glass. The glass in the case of a conical tent occupies the space, triangular in shape, between the center-pole, the outer covering, and the base on which the tent stands. A secret space is thus formed, into which a toy figure, such as a soldier, working on a pivot, controlled, preferably, by a spring, is made to disappear and from which it may be made to reappear at will. I attain these objects by the mechanism illustrated in the accompanying drawings, in which—

Figure 1 is an elevation, Fig. 2 is a plan, Fig. 3 is a side elevation, of glass and mechanism.

B is a base with a slight ridge round edges at bottom to form a hollow space in center. Upon this base is placed a triangular piece of silvered glass C, the perpendicular side of which is fixed at about the center of said base. A covering A is fixed to the front edge of glass at P and carried round to Q, is fastened to base B and also to apex of glass at N, thus leaving an opening in front. Upon the perpendicular edge of glass C is fastened a narrow strip of dark material C', which gives the appearance of a center-pole to the tent.

In the rear of glass C is fixed a block E, through which a pivot F is carried, which extends through base B, having its end bent at right angles F'. The upper end of this pivot is curved round and attached at K to the figure of a soldier D. A portion L is cut out of block E for the purpose of holding pivot F in position when pulled down. A pin J is fixed to block E to hold pivot F in its normal position. To pin H is attached a rubber band G, which is fastened at its other end to figure D.

The toy is thus operated: By turning the pivot F by its bent end F' the figure D is brought round from behind the glass to the front and is reflected in said glass, as shown at D', thus giving the appearance of two soldiers in the tent. By pulling down the pivot F at F' it is kept in position by cut-out portion L. On pressing down the apex of the tent at N pivot F is pushed up in consequence of F' coming into contact with the surface upon which the tent stands, and the figure D is swiftly carried back to its normal position by the tension of the rubber band G, dotted lines M and M' showing this movement.

Having fully described my invention, what I claim, and desire to secure by Letters Patent, is—

The combination of a silvered glass C, with block E, pivot J, spring G, lever F, and figure D, substantially as described and shown.

WILLIAM JINKINGS.
